INWARDLY SWINGABLE, VERTICALLY SLIDABLE WINDOW CONSTRUCTION

Harold A. Etling, Marshallville, Ohio

Application March 30, 1951, Serial No. 218,454

4 Claims. (Cl. 20—50)

1

This invention relates to window constructions, and is particularly directed to double-hung windows wherein the individual window sashes are adapted to have both vertically sliding movement in the window frame and inwardly swinging pivotal movement about one edge of the sash.

The window of the invention is shown as being of the type wherein a window sash is secured to a window frame by means of a pair of slides one of which is associated with the laterally outer edge or vertically extending side of each window sash intermediate it and the adjacent part of the frame. Each sash is shown pivotally secured at one vertically extending edge to one slide and the remaining vertically extending edge is releasably engaged with the slide associated therewith. In order to disengage a sash from its one releasable carrier slide, the slide normally is placed at or adjacent its upper extremity of movement, and retained in such position while the window sash is unlocked from engagement with such slide and moved downwardly of the frame to be completely released from engagement with the carrier slide after a predetermined length of relative movement has occurred between the slide and the window sash.

One type of a pivotal and slidable window similar to the general type referred to is shown and described in my U. S. Patent 2,584,684, while another type of window of this general class is shown in U. S. Patent No. 1,513,657.

The general object of the present invention is to provide an improved window construction of the class described which is characterized by the automatic engagement of a slide member releasably with a portion of a window sash by predetermined relative movement therebetween.

Another object of the invention is to provide a slide member for a window sash, which slide member connects in a novel and releasable manner to a window balance and to the window sash with which it is associated.

Another object of the invention is to provide a window construction of the character described that has novel, sturdy, improved means for engaging a slide member releasably with a window sash.

A further object of the invention is to secure a window balance member quickly and easily and in a releasable manner to a slide member used to secure a window sash in a window frame.

Still another object of the invention is to provide a window of the character described wherein a free edge of a window sash can only be re-

2

leased from its control slide at a desired vertical point.

Another object of the invention is to provide a window of the class described which is made from a minimum of metallic parts and which has desirable operative properties.

Yet another object of the invention is to provide an improved window construction which is of sturdy construction and which is adapted to have a long service life with a minimum of maintenance thereon.

The foregoing and other objects and advantages of the invention will be made more apparent as the specification proceeds.

For a better understanding of the invention, reference should be had to the accompanying drawings, wherein

Fig. 1 is an elevation of a window construction embodying the principles of the invention;

Fig. 2 is an enlarged fragmentary vertical section of an upper corner portion of a window of Fig. 1;

Fig. 3 is an enlarged vertical section taken on line 3—3 of Fig. 2;

Fig. 4 is an enlarged horizontal section of the windows of Fig. 1 on line 4—4 of Fig. 1 with one window slid into overlapping relation with the other;

Fig. 5 is an enlarged fragmentary vertical section through the releasable lock means of the invention; and

Fig. 6 is an enlarged elevation, partially broken away and shown in section, of the lower part of a slide and its associated means.

The present invention relates to a double hung window construction and the invention broadly comprises the combination of a window frame, a pair of window sashes, slides engaging one edge of each window sash to the frame, with slides for the other vertical sides of each of the window sashes, means engaging such last-named slides with the frame for sliding movement, lock means releasably carried by the last-named slides and automatically positionable by gravity for engaging the lower end of the sash to engage same with the frame, a window balance for each of the sashes, and means for securing one of the window balances in a quickly releasable manner to the upper portion of each last-named slide to facilitate securing or changing the balances in the window construction.

Corresponding numerals will be used to identify corresponding parts in the drawings and the specification to facilitate reference between such parts.

Reference now should be had to the details of the structure shown in the drawings, and a window construction which is indicated in general by the numeral 1 is shown and it includes a substantially conventional window frame 2 that has a pair of double hung sashes 3 and 4 positioned therein by means of a pair of slides 5 and 6, and 7 and 8, respectively, for each of the window sashes 3 and 4.

Fig. 4 of the drawings best shows that each of the slides is provided with a vertically extending dove-tail shape in section recess 9, 10, 11 or 12, respectively for the slides 5 through 8, respectively. Such recesses 9 through 12 are engaged with suitable jamb run strips 13, 14, 15 and 16, respectively, in order to engage the slides 5 through 8 for vertical sliding movement on the frame 2. These slides 5 through 8 are received intermediate the laterally outward edges of the window sashes 3 and 4 and the laterally inner surfaces of the window frame 2, as indicated in the drawing. Usually suitable hinges, or butts 18 pivotally engage the window sashes 3 and 4 with the slides 5 and 7, as shown in Fig. 1, so that such vertically extending edge of each of the window sashes 3 and 4 is connected to the window frame for pivotal and sliding movement with relation thereto by means of the slides 5 and 7 and the hinges 18. Of course, when desired, the type of a combined hinge and pivotal or runner strip as disclosed in my above-referred to co-pending application can be used in place of the slides 5 and 7 and the hinges 18 for pivotally connecting one edge of each of the window sashes pivotally and slidably in the window frame.

One important feature of the present invention is that a plurality of spring balances 19 are positioned at the upper portion of the frame 2 and these balances 19 have balance tapes 20, 21, 22 and 23 extending resiliently therefrom for individual engagement with the slides 5 through 8 to aid in positioning them in the window frame to aid in vertical movement of the window sashes 3 and 4. Fig. 3 shows that the balance tape 21 like the other balance tapes of the invention, has a tape end connector, or end portion 24 which is pivotally secured to the tape. Thus each of the slides 5 through 8 has an obliquely directed, or an upwardly and outwardly directed hole or other opening 25 provided therein that extends completely through the slide from the inner to the outer surface thereof with relation to the lateral dimensions of the window of the invention. Such hole 25 is bisected or cut into two portions by suitable means, such as a pin 26, that extends across the hole 25 intermediate the ends thereof. These pins 26 engage the slides to be supported thereby.

Fig. 3 best shows that the end 24 of the balance tape 21 is doubled back around the pin 26 so that the resilient positioning of the balance tapes 20 through 23 urging them upwardly of the window binds or wedges the end portion 24 in the holes 25 to secure the balance tapes releasably to the slides 5 through 8. Such balance tapes can be readily engaged with the slides since the laterally inner surface or edge of each of the slides 5 through 8 can readily be exposed by disengaging the window sashes 3 and 4 therefrom so that the end portions 24 of the tapes can be pulled into the center portion of the frame 2 through the holes 25 after which the tape ends 24 can be doubled back and the tapes be drawn back into the holes 25 until the tape ends are properly positioned around the pins 26. It further will be seen

that at any desired time the tape ends 24 can be pulled laterally inwardly from the exposed end of the hole 25 by a small hook, or the tapes could be pushed inwardly with relation to the slides from the top of the slides so that the tape ends can be straightened out, and the tapes be disengaged from the slides with which they have heretofore been engaged. Fig. 4 shows that the balance tapes 20 through 23 lie intermediate the jamb run strips and the adjacent laterally outer surface of each of the slides. Thus the balance tapes do not interfere with the operation of the window of the invention in any manner and are snugly positioned in a substantially hidden manner in the window construction.

Fig. 5 clearly shows another important element of the present invention which is a releasable means for securing the free or the remaining vertical edge of each of the window sashes 3 and 4 to the slides 6 and 8 to engage same slidably with the frame 2. Thus lock arms 27 and 28 are shown to be pivotally engaged with the slides 6 and 8, respectively, by the pins 29 and 30, respectively. The lock arm 27 has a protruding lock finger 31 that extends laterally inwardly of the window 1 and this lock finger is doubled back upon itself out of a general plane defined by the lock arm 27. A rearwardly or outwardly extending locking lug 32 is also suitably formed on the lock arm 27 for a purpose to be hereinafter explained. The lock arm 28 has a lock finger 33 provided thereon similar to the lock finger or section 31 of the lock arm 27. The construction and arrangement of both lock arms 27 and 28 is such that the lock fingers are normally positioned by gravity to extend laterally inwardly from the remainder of the lock arm and will engage the lower surface of the associated window sashes 3 and 4 when the slides 6 and 8 are laterally aligned and otherwise engaged with the window sashes, as indicated in Fig. 5 of the drawing.

Fig. 5 shows that the jamb run strip 14 has a suitable recess or kerf 34 cut therein at one vertical portion thereof for reception of the lug portion 32 of the lock arm 27 to disengage the lock arm and hence the slide 6 from locked engagement with the sash 3. The kerf 34 usually is of a short or localized length so that normally such lock arm 27 cannot be pivotally moved laterally outwardly with relation to the window sash 3 and thus normally will retain the slide 6 in engagement with the window sash 3 until such sash is moved adjacent to its vertically uppermost position at which time the lug 32 can be swung into the kerf 34 and downward movement of the window sash 3 while the slide 6 is held against movement will disengage same from the slide 6. After complete release from the slide 6, the window sash 3 is free for pivotal movement about its remaining vertical edge and the hinges 18 secured thereto.

Sometimes it may be desired to lock the lock arm 27 in inoperative position and hence a screw 35 or similar member is positioned in the kerf 34 so that a sharp edge portion is provided to engage with a little notch or similar recess 36 provided in the lower part of the lock arm 27 for engagement with this screw 35 to maintain the lock arm 27 in inoperative position. Usually the slide 6 has a limited amount of vertical movement left at the portion of its travel that the lug 32 is received in the kerf 34. Thus when engaging a window sash 3 with the slide 6 by upward movement of the sash, the sash can and will move the

slide 6 vertically a short distance to disengage the lock arm 27 from the screw 35 and permit an automatic gravity locking action or engagement between the slide and the window sash by the arm 27. Usually a small shoulder or stop member 31 is provided on the laterally outer edge of the window sash 3 at the lower end thereof and such shoulder 31 is adapted to engage the lower end of a runner 38 that usually is dove-tail shape in section formed on the laterally inner surface of the slide 6 to provide a positive inter-engagement of the slide 6 and the window sash 3. The slide 8 usually has a runner 39 thereon for similar engagement with the edge of the window sash 4, as indicated in Fig. 4, and such runners 38 and 39 usually extend at least substantially the length of the slides.

In some instances, it may be desirable to have a slightly different type of a release action between the slide 8 and the lower window sash 4. Hence an elongate kerf 40 is shown provided in the jamb run strip 16 with which the slide 8 engages. This kerf 40 is adapted to receive the rear portion of the lock arm 28 therein when same is swung laterally outwardly about its pivot 30.

Accordingly, at any point in the movement of the lower window sash 4, the lock arm 28 can be swung outwardly into the kerf 40 to prepare the sash 4 and slide 8 for separation by disengaging the slide 8 from the window sash 4 by the required relative movement downwardly of the window sash with relation to the slide. Of course, the balance tapes connecting to the slides of the invention will serve to draw such slides normally to the upper portion of the frame 2 when disengaged from the window sashes, or at least to hold the slides in a given position. The lower window sash 4 has means on it, like the shoulder 31, for positively engaging the window sash 4 with the slide 8 when such window sash and slide are properly horizontally aligned by vertical upward movement of the window sash 4 with relation to the slides 8.

It will be appreciated that, when desired, the lock arms 27 and 28 may be provided with suitable means for retaining them in inoperative position and they may be permitted only localized unlocking action. Of course, any desired type of balance means may be used in the window of the invention. The construction shown, it will be noted, is particularly characterized by the minimum of metallic parts provided therein since substantially all of the components of the window can be made from wood, if desired. Any suitable type of sealing means may be provided in any portion of the window and frame means of the invention for sealing the relative components of the window construction with relation to each other. The lock arms 27 and 28 usually are positioned in slots 50 and 51 formed in the lower parts of the slides 6 and 8, respectively. The locking fingers of the lock arms 27 and 28 are offset with relation to general planes defined by the body portions of the lock arms and this enables the lock arms to engage the sashes 3 and 4 offset from the recessed parts of the sashes that engage the runners 38 and 39. Such lower corners of the window sashes can be reinforced in any desired manner.

From the foregoing, it will be observed that a novel type of a slide member has been provided for coupling a window sash to a window frame so that a window balance tape can be readily and easily engaged with or disengaged from the slide

and with the slide being automatically engageable with the window sash at desired times, thus it is submitted that the objects of the invention are achieved.

5 While one complete embodiment has been disclosed herein, it will be appreciated that modification of this particular embodiment of the invention may be resorted to without departing from the scope of the invention as defined by the appended claims.

Having thus described my invention, what I claim is:

1. In a double hung window construction, a window frame, a pair of window sashes, means 15 engaging one vertically extending side of each of said sashes pivotally and slidably to said window frame, slides for the other vertical side of each of said window sashes, means engaging said slides with said frame for sliding movement vertically thereof, lock means releasably carried by said slides and automatically positioned by gravity to engage releasably with the said sash associated therewith at the free edge thereof to engage same with said frame, a spring type window balance 20 for each of said window sashes positioned at the top of said frame, each of said slides having an upwardly and outwardly directed hole provided therein, pin means extending transversely of said hole, and a balance tape extending from each of said balances through said holes and being doubled back around said pin means to be wedged into said hole, said balance tape being releasable from said pin means by being pulled laterally inwardly of said hole and being released from engagement with the said pin means.

2. In a window construction, a window frame, a pair of window sashes, and slide means for each side of each of said window sashes, means engaging said slide means with said frame for sliding movement vertically thereof, hinge means 25 engaging one side of each sash with the said slide means provided therefor, lock means releasably carried by the other of said slide means of each pair of same for any given said sash to releasably engage said sash at the free edge thereof to retain same in engagement with said frame, at least one spring window balance for each of said window sashes, at least one of said slide means for each of said sashes having an obliquely upwardly and outwardly directed hole provided therein, pin means extending transversely of said hole, and balance tapes extending from said balances down along said frame and through said oblique holes in said slide means, end portions 30 of said balance tapes being doubled back around said pin means to be wedged into said hole, said balance means being releasable from said pin means by being pulled laterally inwardly of said hole and being released from engagement with said pin means.

3. In a sliding window construction, a slide bar for engagement between a window frame and a window sash, said slide bar having an upwardly and outwardly directed hole extending therethrough, pin means extending across said hole and engaging said slide bar, a balance tape with a pivotal end portion thereon, said balance tape extending through said hole from the laterally outer surface and having the end portion thereof bent back over said pin means on the opposite side of same as the said tape to be wedged in said hole, said slide bar being releasable from a window sash to expose the inner end of said hole, and balance means engaging the other end of said balance tape.

4. In a sliding window construction, a slide bar for engagement between a window frame and a window sash, said slide bar having an upwardly and outwardly directed hole extending therethrough, pin means extending across said hole and engaging said slide bar, a balance tape with a pivotal end portion thereon, said balance tape extending through said hole from the laterally outer surface and having the end portion thereof bent back over said pin means on the opposite side of same as the said tape to be wedged in said hole, said slide bar being releasable from a window sash to expose the inner end of said hole, and balance means engaging the other end of said balance tape.

7
 4. In a window construction the combination of a window frame, a sash, and slide means for connecting said sash to said frame, said slide means comprising a slide bar, a lock arm with a protruding finger thereon, means pivotally securing said lock arm to said slide bar at a lower end thereof, said finger being positioned by gravity to engage a lower corner of said sash normally to secure said slide bar thereto for unitary movement therewith, said window frame having a kerf in a laterally inner side portion thereof, said lock arm being releasable from engagement with said sash by laterally outward movement of said lock arm into said kerf, and a stationary lock member fixedly engaged with said frame and extending into said kerf, said lock arm having a notched lower surface adapted to receive said lock member to be retained thereby in inoperative posi-

tion, said lock arm being released by said lock member and being moved to its unlocked position by gravity upon upward movement of said slide bar when said lock arm engages said lock member.
